BUCK FOR PRESSING MACHINES

John S. Patterson, Cincinnati, Ohio, assignor to
The American Laundry Machinery Company,
Cincinnati, Ohio, a corporation of Ohio

Application July 30, 1931, Serial No. 553,966

3 Claims. (Cl. 68—9)

My invention relates to a shirt pressing machine and, particularly, to a pressing bed or buck constructed especially for use in pressing the yoke of a shirt. It is the object of this invention to provide a buck adapted for quick and proper pressing of the yoke of a shirt in a single operation and without injury or distortion of shirt parts attached thereto and to provide a buck that may be useful for pressing other parts of the shirt such as the collar of a collar-attached shirt without altering the effectiveness as a pressing bed for yokes.

The yoke of a shirt is the portion that rests on the shoulders of a wearer and terminates in sleeve, back yoke and side shoulder seams, the side shoulder edges of the yoke being sewed to the front of the shirt and extends from the sleeve seams to about the center of each side of the collar or neckband. At this point and from each side of the collar band, the yoke curves inwardly to fit the curve of the collar. The opposite or back yoke edge of the yoke extends from sleeve seam to sleeve seam in usually a straight line at a comparatively short distance from the rear edge of the collar band. Thus, the yoke is a comparatively narrow strip of cloth just wide enough to cover the shoulders and provides the part of the shirt supporting the remainder on the body. The yoke is generally of shirt thickness but due to its peculiar shape and connection with the collar presents quite a problem in high production and quality pressing.

Heretofore, it has been the general practice to press a small square area of the yoke immediately adjacent the rear collar seam by employing a press having a small square buck, the shirt being placed on the buck so that the collar or neckband was behind the rear edge of the buck so as not to be pressed by contact of the heated chest and pressing head. Then, the remaining portion of the yoke from the rear collar seam forwardly to the side shoulder edges would be finished by hand. It would be most desirable to press the collar or neckband and the yoke on the same buck but due to the arrangement of the collar and yoke and particularly the curvature of the seam between the collar and yoke a buck has not heretofore been provided whereon this could be satisfactorily accomplished. For instance, if the collar and yoke are placed upon a buck in an attempt to press them simultaneously and the collar smoothed out, the yoke will of necessity form wrinkles and folds due to the curvature of the collar. Further, after the yoke is smoothed to form a lay, the collar will stand up away from

the buck and be crushed by the pressing operation. Thus, to completely and properly press the yoke of a shirt on the same buck, it is necessary to provide a means which will take care of the collar or neckband of the shirt during the pressing operation and a buck which will accommodate the collar and neckband for pressing without distortion of other prior pressed parts of the shirt.

Various objects and advantageous features of my invention will be seen in the following description and one embodiment thereof may be seen in the accompanying drawings wherein similar characters of reference designate corresponding parts, and wherein:

Fig. 1 is a perspective view of the pressing machine embodying my invention; Fig. 2 is a plan view of a pressing buck constructed in accordance with my invention; Fig. 3 is a view similar to Fig. 2 and showing a shirt with the yoke in position for pressing; Fig. 4 is a plan view similar to Figs. 2 and 3 and showing the collar of a collar-attached shirt applied to the buck in a position for pressing; and Fig. 5 shows a buck constructed in accordance with my invention as forming a part of a triple head press including a cuff buck at each side of the yoke buck.

Referring to Fig. 1 of the drawings, I have shown a pressing machine of the tilting type and of which a buck constructed in accordance with my invention forms a part. However, it will be understood that the buck is equally applicable to use on many other types of pressing machines embodying relatively movable pressing members. The press shown comprises generally a base frame 1 having an upright 2 thereon which carries a heated pressing head or chest 3. The buck 4, which may be of the usual heated type, is arched to form a pressing surface of generally cylindrical form about an axis from front to rear with respect to an operator standing in front of the machine and is mounted on a bracket 5 secured to the upper end of a rod 6 which is supported by a pivotally mounted lever 7, the lever being pivotally mounted on the upright 2 as at 8. Such lever 7 has its free end resting on and engaged by the upper end of a piston rod 9 of a power cylinder and piston construction 10. Suitable means, including treadles 11 and 12 are provided for controlling the operation of a piston in the cylinder 10.

In operation, when the treadle 11 is moved downwardly, the piston in the cylinder is allowed to drop due to the exhaust of fluid pressure from beneath the piston whereupon, due to spring actu-

- ated or other means (not shown) in engagement with the base frame 1 or upright 2, the buck 4 tilts forwardly and a garment may be placed thereon. Then, downward movement of the 5 treadle 12 will result in a supply of fluid pressure to the cylinder 10 to raise the piston to first tilt the buck 4 beneath the chest or pressing head 3 and then exert pressure between the chest 3 and buck 4 to press the garment on the buck. The 10 parts are shown in pressing position.

In accordance with my invention, a pressing bed or buck 4 is formed in the manner shown in Figs. 2, 3 and 4 wherein the rearward side edge of the buck is provided with a recess 14 into 15 which the collar or neckband of a shirt is depressed when the lay is made as shown in Fig. 3. The edges 15 and 16 of the buck are shown slightly curved to more or less conform to the side shoulder edges of a yoke. They lie at an angle to the ends 20 17 and 18 of the buck, the angle being greater than 90° and, therefore, extend rearwardly from the buck ends 17 and 18 to their point of intersection with the contour of the recess 14. Such construction is important in that it provides a 25 buck having an edge that follows the contour of the side shoulder edges of a yoke.

In Figs. 2, 3 and 4 the total depth of the buck 4 is shown to be slightly in excess of the width of the yoke. It has been found to thus be most 30 convenient since, while providing a buck of a width to insure pressing of the entire yoke as shown in Fig. 3, it will permit an operator standing in front of the buck to complete the pressing of both the yoke and the collar band and collar 35 on the same buck without shifting position.

The buck 4 is provided on its opposite edge with a contour particularly applicable to the ironing of other parts of the shirt as, for instance, the collar of a collar-attached shirt or the neckband of a 40 negligee shirt. For example, as shown in Figs. 2, 3 and 4, the front edge 19 of the buck 4 has a contour that conforms substantially to the bottom seam of the collar band of a collar-attached shirt, as shown in Figs. 4 and 5 wherein the collar 45 band and collar of a shirt are shown applied to the buck 4. It will be understood that the rearward edge of the buck 4 may be shaped differently to accommodate shirts having different forms of neckbands or collar bands without departing from 50 the invention.

In pressing the yoke of a shirt, the shirt is placed on the buck 4 as shown in Figs. 3 and 6 with the side shoulder seams 20 and 21 of the yoke in alignment with the edges 15 and 16 of the buck. 55 Then, the ends 22 and 23 of the yoke are smoothed towards the ends 17 and 18 of the buck and the collar 24 is depressed into the recess portion 14 in such a position that the seam 25 of the collar band coincides with the contour of the recess 14. 60 With the yoke in proper position on the buck 4, the buck may be moved into pressing engagement with the usual pressing head, and ironing pressure applied.

Referring to Fig. 5 of the drawings, I have shown 65 the buck 4 of the type just described in combination with and located between spaced cuff bucks 26 on which the cuffs 27 of a shirt may be ironed simultaneously with the ironing of the collar 28 of the shirt as hereinbefore described.

70 With the above construction, I have provided a buck that is particularly applicable to the ironing of yokes and collars of collar-attached shirts, or the yokes and collars of a negligee shirt, and have provided means whereby the yokes of shirts

may be ironed without inconvenience due to the collars or neckbands attached thereto and without injury to the collars or neckbands or distortion of parts of a shirt that have been previously ironed. I have also provided a buck so designed 80 that it is applicable to use in ironing several parts of a shirt as, for instance, both the yoke and the collar or neckband thereof. This is important in that it eliminates the necessity of transferring the garment or article from one machine to another in performing the various ironing operations thereon. The buck is also of an arched 85 shape which will permit a collar and neckband to be ironed thereon and accommodates the curved neckband in such manner that the collar and neckband may be smoothed thereon without necessitating a bunching up of the shirt yoke.

What I claim is:

1. A shirt pressing machine, including a lower garment supporting and pressing bed having an upper pressing surface arched in generally cylindrical form about an axis from front to rear with respect to an operator standing in the front of the machine, the rear edge of said pressing bed being provided with a centrally disposed recess 100 adapted to receive the collar of a collar-attached shirt and on each side thereof being shaped to correspond with the side shoulder seams of a shirt applied to the bed with the yoke smoothed out upon its pressing surface, and the front edge 105 of said bed being shaped to conform to the lower seam of the collar band of such shirt.

2. A shirt pressing machine, including a lower garment supporting and pressing bed having an upper pressing surface arched in generally cylindrical form about an axis from front to rear with respect to an operator standing in the front of the machine, the rear edge of said pressing bed being provided with a centrally disposed recess 110

adapted to receive the collar of a collar-attached shirt and on each side thereof being shaped to correspond with the side shoulder seams of a shirt applied to the bed with the yoke smoothed out upon its pressing surface, the front edge of 115 said bed being shaped to conform to the lower seam of the collar band of such shirt, and the bed, from front to rear, being of such width that when the shirt is dressed thereon with the attached collar within said recess the back yoke seam lies between the front and rear edges of 120 the bed and when the shirt is dressed upon said bed with the neckband seam coincident with the front edge of the bed the collar may be spread out smoothly upon the arched pressing surface 125 without bunching of the shirt yoke.

3. A shirt press having a presser head co- 130

operable with a goods-supporting element, the latter having a pressing surface which is curved in a direction laterally with respect to the press, the top plan contour of which surface is substantially 135 similar to the contour of a shirt yoke, including a recess for allowing the shirt collar to fall below the pressing surface, with the recess facing toward the rear of the press and the area of said pressing surface being not much greater than the 140 area of the yoke and collar of the shirt when flattened, whereby after pressing the yoke, the collar and band can be brought into pressing position by a movement toward the operator while 145 standing at the front of the machine and while facing toward the rear of the machine.

JOHN S. PATTERSON.
